UNITED STATES PATENT OFFICE

EDWARD A. FILENE, OF BOSTON, MASSACHUSETTS

SPEECH TRANSLATING SYSTEM AND METHOD

Application filed May 12, 1930. Serial No. 451,814.

This invention relates to a method and apparatus for use where speeches or the like delivered in one language must be translated into other languages for the convenience or 5 full understanding of persons to whom the subject-matter of the speeches is of interest and importance, and the general object of the invention is to provide apparatus whereby such requirements can be met efficiently.

10 At gatherings such as international conferences, difficulties arise in interpreting the speeches into a number of different languages and much waste of time results from ordinary methods of interpreting under such conditions. According to the usual methods of meeting such a situation, a speech delivered in one language is subsequently interpreted into one or more languages and the overall or 15 total time occupied per speech is greatly increased thereby. Furthermore, this time feature generally precludes interpretation being given in an adequate number of languages where several nationalities are represented. Another important object of the invention is 20 to meet these requirements.

A further object of the invention is to provide an apparatus whereby limitations of prior systems or methods are overcome by making any required number of interpretations simultaneously, and, if desired, simultaneously with the speech itself so that time loss is almost entirely eliminated and the choice of any required number of languages 25 can be provided for without difficulty.

30 Other objects and advantages will appear upon consideration of the following description and of the drawings, in which:

Fig. 1 is a diagrammatic view illustrating a preferred embodiment of the invention;

40 Fig. 2 is a diagrammatic view illustrating one amplifier unit, the microphone connected therewith and one of the language selecting receiving sets; and

Fig. 3 is a diagrammatic view of an auditorium showing a general arrangement of the 45 invention.

The objects of the invention are attained in general in the following manner: All of the 50 translations are made by interpreters suitably positioned with respect to the speaker

and their translations are delivered to the audience by telephony. For this purpose each interpreter is provided with an individual microphone connected through an amplifier to telephone receiving instruments 55 installed at various parts of the hall occupied by the audience, each receiving instrument being provided with selector means whereby any one of the translators may be selected for reception. For example, where interpretations or translations of a speech delivered in German are made into English, French and Spanish, any member of the audience can select the interpretation or translation 60 into the particular language in which he desires to hear the speech, irrespective of the language selected by any other hearer. Also where translations are delivered simultaneously with the speech itself, members of the 65 audience are enabled to receive the speech in the language of their choice irrespective of the language in which the speech is delivered.

In order that the translations of this 70 nature may be made successfully, the interpreters should be placed as close to the speaker as possible. At the same time to enable a number of interpreters to work close together as well as in close proximity of the speaker without mutual disturbance, the individual microphones are provided with 75 silencers or devices designed to prevent ingress of extraneous sounds and egress of the interpreters' voices.

Also, in order that the interpreter may 80 give undivided attention to the task and may not be called upon to attend in any way to the actual operation of the system, automatic control of the system as a whole is provided for, as through the medium of magnetic relays. For example, provision is made whereby the appropriate transmitter is brought 85 into operation by removing the corresponding microphone from a supporting hook and is switched off by returning the microphone to the hook.

The removal of the microphone from the hook and the return thereof to the hook are also utilized to control a language indicator which is located in a position visible to the audience as a whole and indicates the lan- 90

guage being transmitted at any given time. Thus, when an interpreter lifts his microphone to deliver an interpretation or translation, the language appropriate thereto is announced on the indicator; and, if interpretations or translations in a number of languages are delivered simultaneously, each language is indicated in some manner.

To meet practical requirements where writing or note taking are to be carried out by the listener, use should be made of a receiving instrument which leaves the head and hands entirely free but which excludes so far as possible the speaker's voice so that the translation required may be received free from interference. Furthermore to assure the reception of the translation free from interference by the speaker's voice, the transmissions are amplified to a suitable degree before delivery to the audience so that the strength of the reception may always be sufficient to predominate over extraneous sounds and overcome ordinary defects of hearing. Also in order that the actual strength may be adjusted to individual requirements, a volume control device is provided at each receiving instrument without affecting the transmission as a whole.

Referring to Fig. 1 of the drawings, 10 designates the position occupied by the speaker on a platform or stage 11; and 12g, 12f, 12s, 12e, and 12j indicate, respectively, the positions occupied by interpreters or translators to transmit interpretations or translations in German, French, Spanish, English and Japanese. Positioned at the front of the corresponding interpreters' positions are microphones 13g, 13f, 13s, 13e and 13j, and these microphones are connected by suitable input circuits, including wires or conductors 14 with amplifier units 15g, 15f, 15s, 15e and 15j, each of which is provided with means for indicating the language with which it is to be used.

45 In the present diagrammatic showing, German is indicated by G, French by F, Spanish by S, English by E, and Japanese by J; such letters being outlined by opaque material and preferably being formed of transparent material covering the corresponding openings in the opaque material forming sides of language indicators or compartments 16g, 16f, 16s, 16e, and 16j, respectively. These language indicators or compartments are preferably positioned at or above the rostrum or platform and may be independent of each other or may be formed as parts of a single box. Said compartments are individual to these letters and each contains a source of light, controlled in a manner to be described hereinafter. Preferably each letter or the corresponding lamp has a characteristic color. As will be brought out hereinafter, these lamps are lighted only 60 when the corresponding microphones are in

use and the lighting is preferably controlled automatically.

One line in the output circuit of each amplifier unit is connected by suitable branches with a corresponding contact at each of the receiving stations in the system preferably located at the seats or desks in the auditorium. For illustrating the principles of the system, it is considered sufficient to show two receiving stations 17 and 18. The receiving station 17 includes five relatively stationary contacts 17g, 17f, 17s, 17e and 17j, and a movable contact 17m; such stationary contacts being connected respectively with language lines 19g, 19f, 19s, 19e, and 19j of the output circuits of the respective amplifier units, and the movable contact 17m being connected by a common return line 20 connected with the other sides of the output circuits of all of the amplifier units. Obviously by bringing the movable contact 17m into engagement with any of said stationary contacts, the receiving station 17 will be connected with the amplifier unit corresponding with such stationary contact.

The language line contacts 17g, 17f, 17s, 17e and 17j are arranged in corresponding order to the order of the visual indicators 16g, 16f, 16s, 16e and 16j, so that the listener may select the desired language line by noting the relative position of the indicator of the language desired and then selecting the correspondingly arranged language line contact.

Correspondingly, the receiving station 18 includes stationary contacts 18g, 18f, 18s, 18e, and 18j connected respectively with the amplifier unit output lines 19g, 19f, 19s, 19e and 19j; and a movable contact 18m for selective cooperation with these stationary contacts. The receiving stations are arranged at the seats for the audience, and, of course, the entire apparatus is arranged in a suitable auditorium. It is usual in auditoriums of this character to provide each person of the seated audience with a small desk, and the receiving stations may be conveniently arranged at such desks. The seats are within hearing range of the speaker and the speaker is in view of the seated audience.

The system as a whole having been described in a general way, a description will now be given of so much of a preferred embodiment as is necessary in connection with the general description to make the construction and operation clear. In Fig. 2, there are shown a microphone, which will be considered as microphone 13g of Fig. 1; an amplifying unit, which will be considered as amplifier unit 15g of Fig. 1; and a receiving station, which will be considered as receiving station 17 of Fig. 1; and by describing these parts and the connections therewith, the operation of the entire apparatus will be made clear.

The microphone 13g is not shown in detail but is preferably of the same general type as that shown in the British patent to S. G. Brown, No. 29,833, of 1910. Such preferred form of microphone is of the electrodynamic type and consists of a light iron reed adjustably mounted between the poles of the permanent magnet. The reed is secured at one end to the frame of the instrument and at the other to the apex of a small conical diaphragm of the semi-floating type and made of suitable material, such as spun aluminum or thin mica. This combination of reed and diaphragm constitutes a substantially aperiodic couple.

The microphone just described is preferably mounted in a container of water-tight construction so that the mechanism will not be influenced by dampness due to condensation of the breath of the interpreter. The permanent magnet should be wound with a coil of 4000 to 6000 ohms resistance, and, under normal conditions, the vibration of the reed caused by the voice should produce a terminal potential of the order of 2.5 volts between the terminals of the coil.

The microphone should also be fitted with an exterior voice-localizing device consisting, for example, of a small acoustic chamber provided with a mouth orifice of aluminum or other suitable light material. Condensation and any tendency to resonate may be absorbed by sound-dampers of sponge rubber, felt or other absorbent material inserted at the extremities of the acoustic chamber and held in place by detachable end-caps, which permit of renewal when necessary.

Small holes in the sides of the acoustic chamber release internal air pressure caused by speaking into the microphone with the orifice closed by the lips. The holes do not, however, permit any appreciable ingress or egress of sound so that noise or speech in the immediate vicinity does not affect the microphone.

At this point it should be noted that the microphones for the different interpreters are similar and are connected in the same general manner with the corresponding amplifier units.

The hand microphone 13g is suspended, when not in use, on a hook 21 which may be the spring-loaded hook of a switch-pedestal of the usual table type. This hook 21 forms part of a switch 22 in the microphone circuit and, when the microphone is lifted from the hook, the hook is moved upwardly by a spring 23 into engagement with a contact 24, thus closing the circuit at this point. The coil of the microphone is connected in series with a relay 25, a 1/5 ratio transformer 26 and a suitable source of current such as a 4-volt A battery 26a. Upon removal of the microphone 13g from the hook 21, the switch 22 is closed and the relay is energized to shift

its normally retracted armature 27 into engagement with a contact 28 and close another circuit through a suitable source of power, such as said 4-volt A battery 26a. This action of the relay 25 causes the closing of a switch 29 in a circuit 30 containing the lighting means 31 for the language indicator associated with the amplifier unit 15g, and also causes the closing of a switch 32 to connect the amplifier unit with a suitable source of power, as will be described more fully hereinafter.

The switches 29 and 32 may be closed by means of separate relays but are here shown as controlled by a single magnet or relay 33.

The language indicator, taken as a whole, consists of as many parts as there are languages to be transmitted, that is as many parts as there are amplifier units. At the front of each part of the language indicator, is a wall or cover containing a transparent character or letter indicating a language to be transmitted and back of each of said covers is a suitable source of light, such as an incandescent lamp 31. When the relay 25 for any unit is operated, the corresponding relay 33 is operated, the corresponding lamp 31 is connected across the A. C. supply lines and the corresponding transparent indication or letter is illuminated to indicate the language to be transmitted. Preferably the transparent indications or letters are of different colors for the different parts to assist in distinguishing between them. Of course, as previously pointed out, the same general color effects could be produced by using colored lamps.

The transformer 26, which as above stated, is a step-up transformer of 1/5 ratio of transformation, has an impedance matching that of the microphone winding, and raises the potential of the microphone output before it is impressed upon the thermionic amplifier 15g. Preferably, the secondary of this transformer is loaded with a one megohm resistance 34 to improve quality, and a stabilizing resistance 35 of 25,000 ohms is connected in series with the grid connection 36 to prevent self oscillation.

The microphone output is amplified by two pentode tubes 37 connected in parallel. The use of two tubes offers increased current capacity and also increases the reliability of transmission in that the burning out of one tube during operation would not prevent transmission. A pilot lamp 38, connected in parallel with the tube filaments 39 and tinted with the same color as the color determining element of the corresponding part of the language indicator, glows, when the filament potential, which is under the control of a switch 40, is thrown on, and serves as an indicator of proper filament current supply.

The output of the pentode amplifiers is delivered from plates 41 thereof to one or more

receiving stations through a step-down transformer 42 of about 100/1 ratio of transformation. The primary winding of this transformer is matched to the internal impedance of the pentode tubes and the secondary winding is designed to match the impedance of telephone receivers 43 supplied thereby and used at the various receiving stations. To increase the stability of tube operation, the primary winding is shunted, as by use of a 0.5 megohm resistance 44.

For inhibiting a low-frequency oscillation with the consequent periodic thumping sound called "motor-boating", a filter, preferably consisting of a 3 microfarad condenser 45 and a 50 henry iron-cored choke coil 46, is connected in the plate circuit which is supplied from a suitable B battery 47, such as a 180 volt, 2 ampere-hour capacity, storage battery. To prevent inductive interaction between the various amplifying units, each amplifier unit and transformer is enclosed in a metallic box 48 which is grounded. Preferably, the several amplifiers, one for each language transmitted, are housed in a single cabinet.

The grid potential may be given a suitable negative value in any suitable manner. According to the preferred embodiment of the invention, the desired action is obtained, without using a C battery, by connecting a one microfarad condenser 49 and a resistance 50 in parallel between the joint negative terminals of the A and B batteries and the grid connection, thus producing the proper grid bias by the potential drop method. The value of the resistance depends upon the operating conditions in the tubes.

A general check-up on the operation of each amplifying unit may be made by plugging a telephone receiver (not shown) in a test jack 51 connected across the output circuit of the corresponding transformer 42. By testing in this way, the operator is able to determine the quality and volume of each language transmission. The current in the plate circuit is indicated by a milliammeter 52. In addition to the switch 40, the filament circuit is provided with a suitable fuse, such as a 0.5 ampere fuse 52a. The plate circuit is also protected by suitable means, such as a 50 milliampere fuse 53.

The automatic closing of the switch 32, resulting from the removal of the microphone from its hook, effects a connection between A. C. power lines 55 and 56 and devices for charging the A and B batteries during the operation of the amplifier unit. The charging of the B battery is effected by means of a rectifier unit consisting of a copper-oxide rectifier 57, a filter 58, and a transformer 59. The copper-oxide rectifier is connected in bridge formation to give full wave rectification.

The filter 58 consists of a 75 henry iron-

cored choke coil connected in series with a rectifier supply line. A 3 microfarad condenser 61 and a 4 to 6 microfarad condenser 62 are connected across the rectifier supply line at opposite sides of the choke coil. The primary of the rectifier transformer is connected with the A. C. supply lines through the action of a relay as already described. The A battery is charged by another rectifier unit consisting of a copper-oxide rectifier 63 and a transformer 64, but without including a filter; and the primary of the transformer is connected to the A. C. supply in the same manner as the primary of the transformer 59.

Preferably, the transmission lines from the microphones to the amplifier units and from the amplifier units to the receiving stations consist of screened non-inductive wires enclosed in grounded metallic tubing drawn through conduits throughout the auditorium. The transmission lines are connected, at suitable points or receiving stations, to multiple connector sockets 65 from which portable connections of all lines may be made to any receiving position or desk. The transmission on both sides of the amplifier unit is at low potential to reduce the capacitance effects of the wiring system.

As illustrated in Fig. 2, each multiple connector socket 65 includes an individual socket 66 connected with the common return line 20 and a plurality of individual sockets 67 connected with the output transformer circuits of other amplifier units but at the other side thereof from their connection with the common return line 20.

Each telephone receiver set 68 is provided with a multi-contact plug 69 providing an individual plug 70 to cooperate with the individual socket 66 and a plurality of single plugs 71 to cooperate with said individual sockets 67. Such multi-contact plugs 69 are preferably of irreversible design so that they can be inserted only in the positions giving the proper connections.

The various transmission lines connected with each multi-contact plug 69 extend, preferably in the form of a portable cable to a selector switch 72 on a desk (not shown) and forming part of a receiving station 17. The switch 72 is illustrated as of a rotary multi-contact type with each contact identified as to its language connection by a letter associated with the reference numeral applied thereto. The receiving instrument or set is also provided with a volume-control device 73, here shown as a rotary variable rheostat connected in series with the telephone receiver 43. By turning this rheostat each listener may control the volume of the transmitted speech to suit his individual acuteness of hearing.

Preferably, each telephone receiver is an electromagnetic one of about 60 ohms resistance, is of substantially the same construction

- as the microphone transmitter 13g, and is mounted in a small box (not shown) which also contains the corresponding selector switch. Each telephone receiver may include 5 a pair of ear phones. Generally these ear phones are of the stethoscopic type suitably connected to form stethophones which are adapted for use by listeners who wish to have the hands free for taking notes.
- 10 Generally, the various translators or interpreters will be seated side by side before the speaker, each translator being provided with a microphone, such as microphone 13g of which a general description has already been given. The removal of any microphone from a corresponding hook will cause the corresponding language indicator to announce the corresponding language and will energize the associated amplifier unit. A listener at one 15 of the receiving stations, 17 for example, then turns his selector switch to the stationary contact corresponding to the language desired, adjusts the volume by means of the corresponding volume control device 73, and 20 listens to the translation of the speech as it is being delivered in another language.
- According to the illustrative form of the invention the input for each amplifier is controlled directly by a microphone. It should 25 be understood, however, that the rest of the system may be operated irrespective of the particular kind of control for the input of each amplifier.
- It should be understood that various 30 changes may be made in the construction and arrangement of parts and that certain parts may be used without others without departing from the true spirit and scope of the invention.
- 35 Having thus described my invention, I claim:
1. The method of supplying translations of a speech in one language into other languages simultaneously with the delivery of the speech, which comprises transmission of the speech to a plurality of translators corresponding to said other languages, interpretation of the speech into the corresponding other languages by said translators substantially simultaneously with the delivery of said speech, individual selection by each of a plurality of listeners at a corresponding plurality of points of the original speech or of any of the translations, and transmission to said listeners, of the original speech or of the translations in accordance with such selection.
  2. The method of supplying translations of a speech in one language into other languages simultaneously with the delivery of the speech, which comprises transmission of the speech directly to a plurality of translators corresponding to said other languages and positioned adjacent to the speaker where they can readily hear the speech, translation of the speech into the corresponding other lan-
- guages by said interpreters substantially simultaneously with the delivery of said speech, individual selection by each of a plurality of listeners at a corresponding plurality of points within direct hearing range of the speaker of the language of the speaker or of any of the translations, and transmission to said listeners either directly from said speaker or indirectly from said translation in accordance with such selection. 75
3. In apparatus of the class described, the combination of a plurality of translators' microphones arranged adjacent to a speakers' position so that translators using the same can readily hear a speaker in that position, each of said microphones being such that the translation spoken into the same will not be interfered with by the speaker or by the translations spoken into the other microphones, a plurality of receiving stations within direct 80 hearing range of the speaker's position, at each of which any selected translation may be heard by a listener without interference by the speaker or by the other receiving stations, means for transmitting the translations to 85 said receiving stations, and means under the control of the listener at each receiving station for selecting the original speech or the interpreted language for hearing at that station. 90
4. In apparatus of the class described, the combination of a plurality of translators' transmitters arranged adjacent to a speaker's position; a plurality of receiving stations within direct hearing range of the speaker's position; an independent transmitting circuit for each transmitter, each of such circuits leading to all of said plurality of receiving stations whereby each transmitter will be connected by a non-interfering circuit with all 100 of the receiving stations independently of the other transmitters; receiving means at each of said receiving stations including a telephone receiver adapted for preventing interference by extraneous noise; and means at each receiving station for selectively connecting the telephone at such receiving station with any one of said transmitting circuits and disconnecting it from all of the other transmitting circuits. 105
5. An apparatus for transmitting speeches in various languages to an audience, comprising a series of individual microphones into which speech in different languages may be spoken by translators, a series of amplifiers each being individually connected to receive the output of an associated microphone, a series of visual indicators one for each microphone, and a control circuit to each indicator from the corresponding microphone, a series of language lines each being individually connected to the corresponding amplifier and a common return line for all amplifiers, a series of receiving stations with switching devices at each station connecting each station to a 110 115 120 125 130 135

common return line and adapted to be selectively connected to the language lines, said switching mechanism being arranged to correspond with the arrangement of the visual indicator so that a listener can readily establish a connection with a language line which is receiving speech.

6. An apparatus for transmitting speech in various languages to an audience, comprising a plurality of microphones, a plurality of receiving stations selectively connectible to receive the speech delivered into any microphone, and visual indicating devices connected with and controlled by each microphone to indicate to persons at said receiving stations when said microphone is in operation.

7. An apparatus for transmitting speech in various languages to an audience, comprising an auditorium having a speaker's station and a series of seats for the audience, comprising a plurality of microphones adjacent the speaker's station, a plurality of receiving stations at said seats selectively connectible to receive speech delivered into any microphone; and visual indicating devices connected with and controlled by each microphone to indicate to persons at said receiving stations when said microphone is in operation.

8. An apparatus for transmitting speech in various languages to an audience, comprising an auditorium having a speaker's station and a series of seats for the audience, comprising a plurality of microphones adjacent the speaker's station, a plurality of receiving stations at said seats selectively connectible to receive speech delivered into any microphone; and visual indicating devices associated with each microphone and operable to indicate to persons at said receiving stations that the microphone is in use and the language being delivered to the receiving stations from said microphone.

9. In apparatus of the class described, the combination of an auditorium having a speaker's station and a series of seats for an audience, a plurality of translators' microphones arranged adjacent to the speaker's station and adapted to transmit spoken translations of a speech, a plurality of receiving stations at said seats within direct hearing range of the speaker's station, means including amplifiers individual to said microphones for delivering said translations at said receiving stations; a device at each receiving station for selectively connecting the said receiving station with any one of said microphones; and a visual indicating device associated with each microphone and operable to indicate when the microphone is in use and the language being delivered by it to the receiving stations.

In testimony whereof I hereunto affix my signature.

EDWARD A. FILENE.
